UNITED STATES PATENT OFFICE.

ALFRED M. ROEDELHEIM, OF NEW YORK, N. Y.

STOCKING.

1,278,220.

Specification of Letters Patent. Patented Sept. 10, 1918.

Application filed September 27, 1917. Serial No. 193,559.

To all whom it may concern:

Be it known that I, ALFRED M. ROEDELHEIM, a citizen of the United States, residing at New York, in the county of New 5 York and State of New York, have invented a certain new and useful Improvement in Stockings, of which the following is a specification.

This invention relates to stockings, and 10 has for its object to provide a new and improved device of this description adapted for use by men, women, and children, and particularly to eliminate the ordinary garter.

15 The invention is illustrated in the accompanying drawings, wherein—

Figure 1 is a view of a man's stocking embodying the invention;

Fig. 2 is a sectional view taken along the 20 line 2—2 of Fig. 1;

Fig. 3 is a view showing the top of the stocking before the edges are bent;

Fig. 4 is a view showing the invention applied to a lady's stocking.

25 Like numerals refer to like parts throughout the several figures.

As illustrated in the drawing I provide a stocking having a body portion 1 and a top 2, which is preferably a rib top, and which 30 is connected with the body portion in any desired manner.

In Fig. 3 I have shown a top portion showing the full size when made. If this is a rib portion, for example, it will be knit 35 larger in diameter than the body portion, as shown in this figure. Seams 3 are made at the proper distance from the edges, said seams being preferably in alinement with the body portion of the stocking. These 40 seams fasten the two sides of the top portion together, and limit the opening for the leg. Any other method than sewing may be used to secure this result.

The edge sections 4 are then provided 45 with eyelets 5 and are folded over so as to overlap a portion of the top, as shown in Fig. 1.

A lace 6 is then passed through these eyelets and may be laced to tighten the top of 50 the stocking so as to hold it in position without a garter. The lace is preferably fastened to the stocking so as to always be attached thereto, and this may be done by sewing it to the stocking at the point 7, or 55 by fastening it thereto in any other manner. When the stocking is to be washed,

the lace may be unlaced, but is permanently attached to the stocking so that it will also be washed and will always be in position for use. I prefer to cut the lower edges 8 60 of the top portion at an angle as shown, and when the operator is sewing the seams 3, such operator may also sew these edges. These corners may be left uncut or may be tucked in and sewed.

It will thus be seen that the top of the stocking is in a single piece, that nothing is cut away so as to expose the leg in any way, and that the edge sections 4 may have their edges to which the lace is attached 65 substantially parallel if desired, and that therefore a proper tightening effect can be secured. By fastening the lace to the stocking it will be seen that I have here a self-contained device which is always ready for 70 use, which can be easily and quickly tightened so as to be held in proper position without the use of a garter, and which can be made at very little additional expense, thereby saving not only the expense of the 75 garter but the inconvenience and unpleas- 80 antness attending the use of the ordinary garter, particularly the garters used by men which often come down and are exposed to view without the wearer knowing it. The 85 stocking may be full fashioned or seamless.

In Fig. 4 I have shown the device applied to a lady's stocking without a rib top. It is possible, of course, that it may be applied to 90 any form of stocking, and in the specifica- 90 tion and claims where I use the word stock- 95 ing I use this term broadly to cover all forms of hosiery.

When the stocking is made without a rib top the expense of machinery necessary to 95 make rib tops can thus be done away with, and also the labor of transferring and at- 100 taching the rib top to the body portion.

I have described in detail a particular construction embodying my invention, but 100 it is of course evident that the parts may be varied without departing from the spirit of my invention as embodied in the claims, and I therefore do not limit myself to the par- 105 ticular construction shown.

I claim:

1. A stocking comprising a body portion and a top portion connected therewith, the top edge of said top portion being continu- 110ous and uninterrupted, the two opposite sides of said top portion being provided with lacing eyelets and the lacing extending

back and forth through said eyelets whereby the two opposite sides may be drawn toward each other and secured in adjusted position by such lacing.

- 5 2. A stocking comprising a body portion, a top portion, said top portion being wider than the body portion, seams extending longitudinally along said top portion near the outer edges thereof, the edge portions of the top section being folded over so that their free edges are opposed, a lacing extending back and forth between said edge sections by means of which the edges may be drawn toward each other, said lace attached to the
- 10 15 stocking so that when unlaced it will be held against removal.
- 15 3. A stocking comprising a body portion, a top portion made of a single piece and

wider than the body portion, seams extending longitudinally along said top portion 20 near the edges thereof, said seams substantially in alignment with the edges of the body portion, the two edge sections of the top portion having inclined lower ends, said edge sections folded over so that their free 25 edges are opposed, and a lacing extending back and forth between said edges by means of which the edges may be drawn toward each other.

In testimony whereof, I affix my signature 30 in the presence of two witnesses this 18th day of September 1917.

ALFRED M. ROEDELHEIM.
